UNITED STATES PATENT OFFICE.

SHANKER ABAJI BHISEY, OF LONDON, ENGLAND.

TYPE-CASTING MACHINE.

1,146,124.

Specification of Letters Patent. Patented July 13, 1915.

Application filed July 24, 1912. Serial No. 711,331.

To all whom it may concern:

Be it known that I, SHANKER ABAJI BHISEY, a subject of the King of Great Britain, residing at London, in the county 5 of London, England, have invented certain new and useful Improvements in Type-Casting Machines, of which the following is a specification.

This invention relates to type casting machines and has reference particularly to type casting machines in which a plurality of type are cast at each operation and the molds then removed from the casting spout, the types extracted from the molds and delivered 10 to a magazine or collecting device and the molds returned again to the casting position.

A primary feature of the present invention consists of an improved means for withdrawing the types from the molds, the essential characteristic being that the types are withdrawn longitudinally by means of a tang or "break piece" cast integral with the type or alternatively by means of fingers 15 or the like separate from the molds which engage the types and push them out of the molds. The former of these methods renders it possible to employ closed molds, the removal of the types being effected 20 without the necessity for separating the mold parts and another important feature of my invention consists broadly in the provision of a device for forming the nicks in the type, the characteristic feature being 25 that this nick-forming device is automatically introduced into the mold when the types are to be cast and automatically removed from the mold to enable the cast types to be withdrawn without opening the 30 mold. Alternatively the types may be cast without nicks in which case I provide means for cutting the nicks after removal from the molds, the nick cutting apparatus comprising receptacles to which the cast types 35 are delivered and in which they are clamped so arranged that the types are during their 40 passage through the machine automatically carried into and out of engagement with a nick cutting instrument and this instrument may take the form of a rotating cutter or a reciprocating file.

Further features embodied in the machine are a reciprocating abrading device by means of which the bur left at the feet of the type 45 may be removed; a polygonal eccentric for enabling the pressure of the mold against

the casting spout to be adjusted and for compensating for any wear; the provision of a pump controlling cam with projections which so coöperate with small rollers on the 50 pump lever as to insure a rapid release of the pump plunger under the influence of its spring, the arrangement preferably being such that the pump plunger is allowed to descend sufficiently to close the inlet 55 openings to its cylinder before the plunger is finally released; the provision of means for enabling the stroke of the pump to be adjusted and the fastening of the molds upon an L shaped mold support by means 60 of screws set diagonally.

In the accompanying drawings a machine embodying these features is illustrated.

Figure 1 is an elevation partly in section of a machine constructed according to my 75 invention. Fig. 2 is a half plan thereof projected from Fig. 1. Fig. 3 is an elevation, partly in section, of part of the machine showing the mold opened for the ejection of the type. Figs. 4 and 5 illustrate one 80 construction of mold and a method of securing it in place. Figs. 6 and 7 illustrate another construction of mold and another method of securing it in place. Fig. 8 is a sectional elevation of mechanism for cutting notches in the type. Fig. 9 is a sectional plan of a modified form of mechanism for effecting the same object. Figs. 10 and 11 illustrate a method of varying the stroke of the force pump for injecting 90 the molten metal into the molds. Fig. 12 is an end elevation of the mold carriage and molds of a modified construction of the machine looking from left to right of Fig. 6. Fig. 13 is a section of the molds and 95 mold carriage of this modified construction and its connections. Fig. 14 is a similar view to Fig. 13 showing the mold open. Fig. 15 is an end elevation of the mold carriage and molds of a third modification of 100 construction of the machine. Fig. 16 is a plan of Fig. 15. Fig. 17 is a section of the mold and mold carriage of this modified construction and its connections. Fig. 18 is a similar view to Fig. 17 showing the 105 mold open. Figs. 19 and 20 are details of the adjusting mechanism for one of the rollers.

Referring particularly to Figs. 1-9 the numeral 1 designates the cam shaft and 2 the mold carriage which is slideable to and 110 from the casting spout 3 in guides 4 carried

by the framework of the machine. The molds (Figs. 4-7) are built up upon the carriage 2 of the body plates 5 and division walls 6 are permanently closed—in this example—by the cover plate 7. The molds (Figs. 4-7) are secured to the mold support 8 by means of screws 9 set diagonally so as to press the molds simultaneously against both the base and the back of the support 8. These screws 9 may pass down into the mold support as shown in Fig. 4 or may pass upwardly through the mold support into the mold, a brass bush 10 being set transversely in the mold to receive the inner end of the screw as shown in Fig. 6. The matrices 11 are mounted within a bar 12 of channel section which is suitably secured to the back of the L-shaped mold support 8. The arrangement of the molds and matrices is preferably such that they can be bodily moved from the mold carriage. The numeral 13 designates a convenient form of nick forming member which consists of a cylindrical bar 13 provided with a flat face 14 which runs through all the molds. Keyed upon this nick forming bar a pinion 15 is arranged which gears with a quadrant 16 in a manner which will hereafter appear so that when the types are being cast a portion of the bar 13 protrudes and when the types are completed the bar is turned so as to bring the flat face 14 in line with the inner face of the cover plate and thus no obstruction is offered to the withdrawal of the cast types. It should be noted that this particular means for forming the nick is given by way of example but any construction which involves the automatic introduction into and withdrawal from the mold of a nick forming obstruction falls within the scope of my invention.

Hinged to the bar 12 a hinged bracket 17 is provided and a spring 18 is interposed between this bracket and the bar 12 and serves to take up any backlash and insure the steady pressure of the mold against the casting spout 3. Lugs 19 project from the bracket 17 and in slots 20 in these lugs bearing blocks 21 are located and these bearing blocks carry the spindle 22 of a roller 23 which roller co-operates with the cam 24 which controls the movement of the mold carriage and support toward the casting spout. Upon the same spindle 22 polygonal blocks 25 are eccentrically mounted and can by means of set screws 26 be secured in various positions abutting against the bracket 17. It will be obvious that by turning these eccentric polygonal blocks 25 the position of the roller 23 relative to the cam 24 can be adjusted within the limits of the eccentricity of the blocks 25.

The further important constructional features of the machine will best be understood and appreciated if described in relation to

the operation of the machine which is as follows: Cams 27 on the shaft 1 operate in conjunction with rollers 28 on the end of pivoted pump levers 29 and cause the pump plunger (not shown) to be lifted against the influence of a spring and the cam 24 on the shaft 1 operates in conjunction with the roller 23 to close the mold against the casting spout 3. Assuming the mold to be closed the cams 27 reach the point where they release the pump plunger, that is to say, the point where the rollers 28 drop off the largest diameters of the cams 27. Ordinarily the release of this roller occurs somewhat slowly owing to considerable radius of the rollers 28. To obviate this and insure a more rapid release I provide on the pump cams near their release edges, lateral projections 30, terminating in corners of small radius, which projections co-operate with small rollers 31 on the pump lever 29. The form of the cam 27 and projections 30 is preferably such that it permits the pump plunger to fall sufficiently to close the inlet openings from the melting pot to the pump cylinder before the release of the pump plunger occurs. The release of the pump plunger will cause metal to be ejected from the casting spout 3 into the mold cavities and the type will be cast as will be readily understood. Cams 32 now operate in conjunction with the rollers 33 carried upon a link 34 proceeding from the mold carriage and support and the mold moves away from the casting spout, the supporting levers 35 rocking about their pivotal points 36 and 37. For a portion of the movement, the whole of the mold parts move away from the casting spout until an eye 38 connected to the break bar 39 of the mold, is arrested by the hook 40 and prevented from further movement, whereupon the rest of the mold continues its movement and the type 41 is withdrawn by the engagement of its tang or break piece 42 with the break bar 39. Before however this withdrawal of the types takes place the quadrant 16 will have turned the pinion 15 keyed upon the nick forming bar 13 sufficiently to turn the flat 14 of the nick forming bar into the position previously occupied by the nick forming portion of the bar, thus this nick forming bar will form no obstruction to the withdrawal of the types.

The movement of the quadrant 16 is effected in the following manner: The upper end of the quadrant is provided with a nose 43 which, when the mold is closed against the casting spout, is engaged in a notch 44 in a bracket 45 rigidly secured to the frame of the machine. The quadrant is pivoted to the movable mold carriage and thus moves bodily with the mold carriage and by reason of the engagement of the nose 43 in the notch 44 the quadrant 16 also moves about its pivot and operates the pinion 15 with 120

- the before described result. When the pinion has been turned sufficiently the nose 43 will become disengaged from the notch 44. On the hook 40 is a small nose 40^a just behind the vertical portion 40^b. The vertical portion 40^b when free projects slightly above the guide slot 2^a by the upper side of which it is depressed during the motion of the mold carriage toward the casting spout.
- 5 Before the break bar reaches the position shown in Fig. 3 the vertical portion 40^b is released and the nose 40^a rises behind the eye 38 thus preventing the break bar from returning until the mold parts have or have almost reached it. Springs 39^a may be provided for allowing of expansion of break bar between slipper 39^b and break bar.
- 10 The types thus withdrawn from the molds by means of the break pieces are detached from the break piece or tang and delivered to a chute 61 in the following manner: A breaking lever 46 pivoted to a bracket upon the mold is provided at its upper end with a roller 47 and at its lower end with a breaking member 48. The roller 47 is by means of a spring maintained in contact with the under surface of a member 49 which is pivoted at 50 to the bracket 51 and is secured against movement by a pin 52 passing through holes in it and in the bracket. The object of this particular arrangement is to enable the member 49 to be turned out of the way when it is desired to remove the molds from the support or carriage. As the molds 20 move away from the casting spout the roller travels along the path 53 and when it reaches the part 54 the breaking member is depressed sufficiently to contact with the upper surface of the type. Simultaneously the chute 61 is raised and exerts an upward pressure in a different plane by reason of a cam 55 coöperating with a roller 56 upon the upper end of a pivoted spring controlled lever 57. This action causes the end 58 of the 25 lever 57 to rise against the roller 59 upon the lower end of the chute 61 thus causing the chute to bodily rise through its guide in the bracket 60 beneath and to one side of the molds. The types will thus be detached from the break pieces or tangs and at the same time tilted so as to fall into the chute 61. On its return movement the member 48 sweeps off the tangs or break pieces, small 30 projections 42^a being cast upon the break pieces 42 which projections are engaged by the member 48. The bottom of the chute 61 is closed by a plate 62 which when the types are discharged into the chute is held by the spring 63 in the position shown in Fig. 3 closing the chute. When however the molds move back again into contact with the casting spout carrying the chute 61 and its connections with them, the end of the plate 62 contacts with the stop 64 on the framework 35 of the machine, the spring 63 is compressed and the opening 65 in the plate 62 comes into position coincident with the bottom of the chute and the types fall out into a magazine or other receptacle designed to receive them. As the roller 59 in its movements has 70 to run on and off the end 58 of the lever 57, the upper surface of the end 58 of this lever is preferably inclined somewhat to give a lead to the roller.
- 75 Although it is generally advantageous to form the nicks in the type during the casting operation, the types may be cast without nicks and the nicks formed by cutting afterward. Means for enabling this nick cutting to be performed are illustrated in Figs. 80 8 and 9. In Fig. 8 the arrangement consists of a chute 66 down which the cast types pass which may be the chute 61 but is preferably another stationary chute 66 located beneath the chute 61. A spring 85 pressed pressure block 67 having a projection 68 operates through openings in the wall of the chute 66. The projection 68 catches the types as they fall and the block 67 forces them against a file or nick cutting 90 instrument 69. The file or nick cutting instrument 69 rapidly reciprocates and forms the required nick or nicks. A part of the instrument 69 may be formed as a beveled file surface 70 which will serve to remove 95 any burr on the feet of the type due to the detachment of the break piece. When the nick forming and abrading operations have been completed, the pressure block 67 is moved back against the action of its spring 100 by the lever 71 and the types are allowed to fall. The portion 67^a on block 67 serves to withdraw type from files when the nicks are completed. The file instead of reciprocating may be in the form of a band file traveling 105 continuously as shown at Fig. 9. The continuously running chain 72 carries a number of small files 73 each having nick forming and abrading surfaces which protrude into the chute 74 which corresponds to the chute 110 66 shown in Fig. 8. The chute 74 is provided with an exactly similar arrangement for catching and holding the type in position against the cutting and abrading surfaces as that shown in Fig. 8. That is to 115 say, a spring pressed presser block 75 catches the type and forces it against the opposite wall of the chute while the files operate upon the type and a lever 77 similar to the lever 71 operates to move the presser block 75 back and thus the type is permitted to fall. The chutes 61, 66, and 74 are preferably 120 provided with ribs such as 74^a as shown in Figs. 8 and 9 which extend sufficiently into the chutes to form separate compartments 125 for each type. The size of the chutes and the extent to which the ribs 74^a extend into the chutes will depend on the cross section of the type being cast. In Fig. 9 the types are shown rectangular in cross section. 130

The provision of a permanently closed mold gives manifest advantages but it also involves difficulties particularly in the matter of forming the nicks in the type. If 5 desirable therefore a machine embodying the essential features of my invention may be constructed with a removable cover plate. Such constructions are shown in Figs. 12 to 18.

10 Referring to these figures the cover plate 78 is provided with a nick forming protrusion 79 integral with it. During the casting operation the cover plate 78 is held firmly down by means of the engagement of 15 the levers 80 operated by the cams 81 with the rollers 82 which are carried by the lower ends of rods 83 connected at their upper ends to a yoke 84 which presses upon the cover plate 78 of the mold. When however 20 the types are to be withdrawn from the molds the rollers 85 fall off the surfaces 86 of the cams 81 and springs 87 force the cover plate 78 up and move the protrusions 79 out of engagement with the nicks in the cast 25 types. Thus the types are free to be withdrawn by means of their tangs or break pieces precisely as in the previously described construction. That is to say, cams operate in conjunction with rollers carried 30 by the mold carriage to reciprocate the mold to and from the casting spout 88. A hook 89 operates to arrest the movement of the break forming member 90 of the mold and while the rest of the mold parts continue 35 their movement leaving the types attached to the break forming member, levers 91 having a break bar 92 operate by the co-action of the rollers 93 with the surfaces 94 to detach the types from their break pieces while 40 the chute 95 rises to assist the breaking or detaching operation and also insures the tilting of the type in the chute.

It is sometimes desirable in machines of this character to be able to adjust the stroke 45 of the metal ejecting pump. A means for effecting this is shown in Figs. 10 and 11. The pump plunger is raised against a spring and released to eject the metal. Therefore the effective stroke of the pump is determined by the distance the pump plunger is allowed to fall under the influence of its 50 spring. In order to render this distance variable I provide wedges 96 which may have graduation markings 97. These wedges 55 are arranged beneath the pump plunger rods and are connected together by means of a yoke 98 having a tapped opening 99. By means of the screw 100 adapted to be rotated by the handle 101 these wedges can be 60 adjusted in position with various parts of their inclines controlling the stroke of the pump.

In Figs. 15, 16, 17 and 18, I have shown a construction of open mold apparatus 65 where the cast types are withdrawn from the

mold by means of fingers which enter the mold cavities. Referring to these figures the numeral 102 designates the molds, 103 is the mold cover and 104 the break bar of the mold. The mold cover 103 is during 70 the casting operation held down by the yoke 105 which is connected to the pivoted levers 106 by the rods 107, rollers 108 on the end of the levers 106 coöperating with cams as clearly shown in Figs. 17 and 18, 13 and 14. 75 The arrangement in the present example is substantially the same as in the prior described example except that the yoke 105 does not move with the mold carriage 110, roller bearings 109 being provided to render easy the movement of the mold carriage 110 relative to this yoke 105. After the types have been cast in the mold in the usual manner, the mold cover 103 rises under the influence of the springs 111 the rollers 108 slipping off the larger diameters of their coöperating cams as will be readily understood. The mold then bodily moves clear of the casting spout after which the movement of the mold body is arrested. 80 During this movement the break bar 104 of the mold moves with the mold but is connected by means of the lever 112 with the framework of the machine with the result that it is pulled down somewhat into the 85 position shown in Fig. 18. This downward movement of the break bar 104 causes the types to be severed from the break pieces, the types remaining in the mold. Fingers 113 which are preferably interchangeable 90 are carried by rods 114 which telescope in the hollow members 115 of bell crank levers 116 pivoted at 118. Rollers 119 on the ends of these levers coöperate with cams and the fingers 113 are by means of these cams 95 brought into engagement with the mold carriage pins 120 being provided to engage grooves 121 in the carriage. The lower ends of the fingers 113 are now behind and in line with the cast types lying in the mold 100 and as the carriage continues its movement the fingers enter the mold cavities and push out the types, the mold body remaining stationary while the mold cover 103 and the matrix and its rod 114 and hollow members 115 move with the mold carriage. Obviously instead of the fingers moving to extrude the type, the arrangement may be such that the mold moves and the fingers 113 remain stationary. It will be understood that 105 the finger carrying rods 114 telescope into the hollow members 115 of the bell crank levers 116. The types thus pushed out of the molds by the fingers 113 are deposited upon a pivoted platform 117 which by means of 110 a spring tends to rise to the position shown in Fig. 18, but is depressed into the position shown in Fig. 17 as the matrix and its carrier moves back to the casting position. From the platform 117 the type passes to a 115

second pivoted platform 122 which is, by means of the link 123 and the bell crank lever 124 and the roller 111, actuated by a cam 125 on the cam shaft and the formation of this cam is such when the mold parts and connections return to the casting position the platform 122 is tilted to the position shown in Fig. 17 when the type falls into the collecting chute 126. It will of course be understood that the details of construction of my invention may be varied in many ways within the scope of my claims, the particular arrangements shown and described being given merely by way of examples.

What I claim and desire to secure by Letters Patent is:—

1. In a type casting machine, a casting spout, a mold adapted to cast a type with a break piece, means for ejecting metal from the spout to the mold, and means coöperating with the break piece of the cast type for withdrawing the cast type from the mold substantially as specified.
  2. In a type casting machine a casting spout, a mold having a break forming member movable relative to the casting spout, means for moving the mold and the break forming member relative to the casting spout, and means for arresting the movement of the break forming member and permitting the mold proper to continue its movement whereby the type is positively withdrawn from the mold by the break piece substantially as specified.
  3. In a type casting machine a casting spout, a mold having a break forming member movable relative to the casting spout, means for moving the mold and the break forming member relative to the casting spout, means for arresting the movement of the break forming member and permitting the mold proper to continue its movement whereby the type is positively withdrawn from the mold by the break piece and means for detaching the type from its break piece substantially as specified.
  4. In a type casting machine a casting spout, a mold having a break forming member movable relative to the casting spout, means for moving the mold and the break forming member relative to the casting spout, means for arresting the movement of the break forming member and permitting the mold proper to continue its movement whereby the type is positively withdrawn from the mold by the break piece, means for exerting a pressure upon the upper surface of the type in one plane, a vertically mov-
- able chute located beneath the type and designed to receive it, means for moving the chute to exert an upward pressure upon the under surface of the type in a plane other than that in which the pressure is exerted upon the upper surface of the type whereby the type is simultaneously detached from its break piece and tilted into the chute substantially as specified.
5. In a type casting machine, a mold, means for injecting molten metal into the mold, a partially cylindrical nick forming member provided with a flat face, and means for rotating the nick forming member to automatically turn the cylindrical portion into the mold cavity during the casting operation, and to turn it out of the mold cavity to enable the type to be withdrawn.
  6. In a type casting machine, a casting spout, a reciprocable mold carriage having an L shaped mold support, a mold fitting upon the L shaped mold support, a screw connection between the mold and the support set diagonally whereby the mold is pressed simultaneously both against the base and back of its support, and means for removing the cast types from the mold substantially as specified.
  7. In a type casting machine, a casting spout, a mold reciprocable relative to the casting spout, cams operable to reciprocate the mold, a roller associated with the mold and coöperating with a cam to cause the mold to be pressed against the casting spout, a polygonal eccentric associated with the roller whereby the position of the roller relative to the cam can be adjusted, and a second roller associated with the mold and coöperating with a cam to cause the mold to move away from the casting spout and permit the withdrawal of the cast type substantially as specified.
  8. In a type casting machine a casting spout, a mold having a break forming member movable relative to the casting spout, means for moving the mold and the break forming member relative to the casting spout, and means for effecting movement of the break forming member relative to the mold proper whereby said break forming member and mold proper separate and the type is positively withdrawn from the mold by the break piece substantially as specified.

In testimony whereof, I affix my signature in the presence of two witnesses.

SHANKER ABAJI BHISEY.
